AMBROSE G. FELL, OF BROOKLYN, NEW YORK, ASSIGNOR TO HIMSELF
AND WILLIAM BELL, OF NEW YORK, N. Y.

Letters Patent No. 66,230, dated July 2, 1867.

IMPROVEMENT IN WATER-INDICATORS FOR BOILERS.

The Schedule referred to in these Letters Patent and making part of the same.

TO ALL WHOM IT MAY CONCERN:

Be it known that I, AMBROSE G. FELL, of the city of Brooklyn, in the State of New York, have invented a new and improved Water-Gauge for Steam Boilers; and do hereby declare the following to be a full, clear, and exact description thereof, reference being had to the drawings which accompany this specification and to the letters and figures marked thereon. Of these drawings—

Figure 1 represents a front elevation of the gauge, and

Figure 2 a cross-section.

Water-gauges for steam boilers have been heretofore constructed with a glass tube, which is objectionable for many reasons, such as liability to fracture from flying pieces of coal, from sudden changes of temperature, and by the crumbling or wearing away very rapidly at the ends, occasioned by the great heat these points are subject to and the corrosive effects of the steam thereon, besides the well-known liability to fracture after cleaning. When a glass tube becomes broken it is necessary, especially on ship-board, to replace it while the boiler is hot, consequently making the operation difficult, having to work so close up to the boiler; and sometimes in breaking they scald the men. It is found necessary with glass gauges, when a steamer is leaving port, to carry along a box full of tubes, because of the necessity of frequent replenishment. My gauge is therefore more economical, as one will last as long as the boiler itself. Flying pieces of coal, great changes of temperature, &c., will not affect it; besides it will, being constructed in part of mica, stand a greater pressure than the glass gauge, such having been found to be the fact by actual tests.

To enable others to make and use my invention, I will proceed to describe its construction.

A is the frame of the gauge cast with an adjutage or nozzle, $a a'$, at each end for the attachments to the boiler. B B are the faces or sides of the gauge, in each of which is a slotted opening running the whole length of the device so as to enable a person to look through the gauge. These faces or sides are firmly screwed into the frame A, perfect strips of mica, C C, of the same size as the sides B B, with thin strips of rubber or other suitable material, placed underneath and along the edges thereof, being first inserted between.

The whole four faces or sides, or one face alone, can be constructed with mica, if desired, but the arrangement here shown permits of a person looking through the gauge as with the ordinary glass tube, though with the use of only one side of mica the height of the water in the boiler is easily discerned.

What I claim as new, and desire to secure by Letters Patent, is—

The construction of a water-indicator for steam generators, having one or more sides of mica, substantially as and for the purpose herein set forth and described.
